United States Patent Office

Des. 183,140
Patented July 1, 1958

183,140

LACE FABRIC OR SIMILAR ARTICLE

Robert Arthur Padmore, Scranton, Pa.

Application March 26, 1957, Serial No. 45,444

Term of patent 3½ years

(Cl. D47—6)

The figure is a plan view of a lace fabric showing my new design, a full width being indicated by the top and bottom margins, and the pattern repeating in a sidewise direction as shown.

I claim:

The ornamental design for a lace fabric or similar article, as shown and described.
